Inventor:
Richard T. Foley,
by his attorney,
Charles R. Searle.

UNITED STATES PATENT OFFICE.

RICHARD T. FOLEY, OF RIDGEFIELD PARK, NEW JERSEY.

VALVE.

Application filed February 12, 1924. Serial No. 692,289.

To all whom it may concern:

Be it known that I, RICHARD T. FOLEY, a citizen of the United States, residing in Ridgefield Park, in the county of Bergen and State of New Jersey, have invented a certain new and useful Improvement in Valves, of which the following is a specification.

The invention relates to self-seating valves and faucets for water, steam and other fluids, and the object of the invention is to provide a spring actuated valve of simple construction which shall operate easily and hold efficiently. Another important object is to provide antifriction means for lifting the valve-plug from its seat, and a further object is to provide a structure in which such seat is easily accessible in the process of manufacture.

The invention consists in certain novel features and details of construction and arrangement by which the above objects are attained, to be hereinafter described and claimed.

The accompanying drawings form a part of this specification and show the invention as applied to a basin faucet.

Figure 1 is a side elevation of the improved faucet.

Figure 2 is a corresponding vertical section through the working parts of the same.

Figure 3 is a plan view of the cap by which the valve plug is lifted from its seat.

Figure 4 is a plan view of a portion carrying the antifriction balls serving as the abutment for such lifting operation.

Figure 5 is a plan view of the under face of a movable disk adapted to ride upon the balls and induce the lifting of the plug.

Similar reference numerals indicate the same parts in all the figures.

The body 6 of the valve is shown as having the form of a basin faucet of a well-known type, having the usual delivery spout 7 and a screw threaded extension 8 by which it is secured to a basin slab in the usual manner.

The body 6 is provided with a horizontal partition 10 having a central opening 9 and adapted to serve as a seat 11 for the vertically movable valve plug 12. The upper part of the body 6 is open to permit easy access to the seat in the operation of shaping the latter by any suitable lathe tool or otherwise, and is tapped to receive the lower end

of a tubular casing 13 forming an upward extension of the body.

The casing 13 has a flanged head 14 in which is a centrally located circular opening 15 serving as a guide for the cylindrical portion of the valve stem 16 which is received therein with liberty to move vertically therethrough. In the upper face of the head 14 are a plurality of hemispherical cavities 17, four are shown, each loosely receiving a hardened steel ball 18.

A collar 19 incloses the lower end of the valve stem 16 at its junction with the plug 12 and rests upon the shoulder 33 thus formed; the collar 19 serves as a guide for the plug and also as an abutment for one end of the helical expansion spring 20 encircling the stem 16 and abutting at the other, upper, end against the under face of the head 14. The spring exerts its force downwardly to hold the plug 12 to its seat 11 and close the passage 9.

The valve stem 16 is squared at the upper end as at 21 and passes through a square hole 22 in the centre of a disk 23. The disk 23 has deep cavities in its under face receiving the semispherical upper portions of the balls 18. These cavities or depressions are preferably in the form of grooves 24 extending diametrically across the disk at a right angle to each other, and in the line of the circle described by the balls are inclined notches or paths 25 leading laterally from the grooves 24 to the plane portions of the under face of the disk, see Figure 5. The disk 23 is engaged with the squared portion 21 of the valve stem and is compelled to move with the valve plug as the latter is partially rotated.

A cap 26 inclosing the disk 23 and head 14 extends below the latter. It has a centrally located square opening through which the squared portion 21 of the stem extends, and is held in place thereon by a nut 27 engaged with a screwthreaded extension 28 on the end of the stem. The under face of the cap lies close to the upper face of the disk 23 and holds the latter down upon the balls 18. It will be noted that when the cap 26 is partially rotated in either direction by grasping the arms 29 thereof the valve stem is correspondingly moved and the disk 23 compelled to partake in such movement. The partial rotation causes the disk 23 to ride up on the balls 18, carrying the cap 26

with it in the upward movement and also the valve stem and plug, thus compressing the spring 20 and lifting the valve from its seat in opposition to the spring.

8. When the cap is released the tension of the spring 20, with the inclination of the notches 25, induces a return movement of the cap and disk 23 to receive the balls 18 again in the grooves 24 and permits the plug 10 to descend upon its seat 11 and stop the flow.

It will be noted that the balls 18 while rotatable in the cavities 17 do not travel or change their position laterally or vertically, 15 the required vertical movement of the plug 12 being induced by the action of the grooves 24 and inclined notches 25 of the disk 23 riding upon the relatively stationary balls.

20. The skirt or depending cylindrical flange 30 of the cap 26 is internally screwthreaded and extends sufficiently below the relatively fixed head 14 to receive an internal collar 31 encircling the casing 13 and serving by 25 its contact with the under face of the flange of the head to limit the upward movement of the cap and its connected parts. The collar 31 is screwed in place by the application of a suitable spanner, not shown, engaged with the apertures 32.

Although the invention is shown and described as applied to a basin faucet it will be understood that it may be applied to any type of valve with which it is adapted to 25 serve in controlling the flow of various fluids.

I claim:-

1. A valve comprising a body having a valve seat, a casing separably mounted on 40 said body in axial alinement with said seat, and having a head, a valve plug having a stem extending through said head, a series of balls loosely seated in cavities in said head, a disk having depressions receiving 45 the protruding portions of said balls, said

disk arranged to ride upon said balls and lift said plug by a turning movement of said stem, said balls being retained against movement from their positions during the movement of said disk, and a cap secured to said stem to turn and to rise and sink therewith and inclosing said disk and head.

2. A valve comprising a body having a valve seat, a casing separably mounted on said body in axial alinement with said seat, 55 and having a head, a valve plug having a stem extending through said head, a series of balls loosely seated in cavities in said head, a disk having depressions receiving the protruding portions of said balls, said disk 60 arranged to ride upon said balls and lift said plug by a turning movement of said stem, said balls being retained against movement from their positions during the movement of said disk, a cap secured to said stem 65 to turn and to rise and sink therewith and inclosing said disk and head, and having a depending skirt, and an annular collar inclosing said casing and engaged with said skirt within the latter, and arranged to contact with said head to limit the upward movement of said plug.

3. A valve comprising a body with valve seat, a casing mounted thereon, and having a head with hemispherical cavities, balls 75 seated therein, a valve and valve stem, a spring surrounding the valve stem and interposed between a shoulder thereon and a shoulder on said head, a disk mounted on the stem and having in its under face grooves 80 receiving and matching the upper portions of the balls, said grooves extending diametrically at right angles to each other, and inclined notches leading from said grooves to the portions of the under face of the disk between said grooves, and a cap bearing on 85 said disk.

In testimony that I claim the invention above set forth I affix my signature hereto.

RICHARD T. FOLEY.
